UNITED STATES PATENT OFFICE

WILLIAM A. COPELAND, OF BOSTON, MASSACHUSETTS, ASSIGNOR TO INTERNATIONAL SHOE COMPANY, OF ST. LOUIS, MISSOURI, A CORPORATION OF DELAWARE

MACHINE FOR TREEING BOOTS AND SHOES

Application filed August 7, 1925. Serial No. 48,716.

This invention relates to machines for treeing boots and shoes and while not limited thereto has been more particularly designed for use in connection with treeing machines of the general type disclosed in Patent No. 5 691,576 granted January 21, 1902, to Harrie A. Ballard, for machine for treeing boots or shoes and relates, more specifically to the construction and mounting of the shoe-engaging tools by which they are better adapted to 10 closely follow the contour of the shoe during the operation of the machine. A further feature of this invention relates to a construction by which treating of the tool is 15 facilitated.

For a more complete understanding of this invention, together with further objects and advantageous details of construction, reference may be had to the accompanying drawings in which

Figure 1 is a side elevation of a treeing machine embodying the subject matter of this invention.

Figure 2 is a fragmentary perspective 25 illustrating the engagement of certain of the treeing tools on the shoe.

Figure 3 is a side elevation of the back treating tools and their mountings.

Figure 4 is a perspective of a pair of back 30 treating tools.

Figures 5 and 6 are detail sections on lines 5—5 and 6—6, respectively, of Figures 4, but showing the mounting devices for the tools.

Figure 7 is a section on line 7—7 of Figure 5.

Figure 8 is a side elevation of a forepart treating tool and its immediate mounting.

Figure 9 is a similar view of a rand tool. 40 Figures 10, 11 and 12 are perspective views showing various constructions of tool supports or carriers.

Figures 13 and 14 are detail plans of the devices shown in Figures 8 and 9, respectively, looking in the directions of the arrows.

As shown more particularly in Figure 1 the machine comprises a base 1 having a standard 2 at one end on which is supported for rotation in a horizontal plane, a turret 50 3, having radially extending treeing forms

4 on which may be carried the boots or shoes as at 5 to be treed. Adjacent to the opposite end of the base 1 is a standard 6 which supports the holding and operating devices for the treeing tools which operate on a shoe carried by one of the treeing forms 4 when this treeing form is swung into proper relation thereto.

The standard 6 has a vertical slideway 7 formed near its upper end on which is mounted a vertically traveling slide or carriage 8 on which are supported the forepart treeing or ironing tools 10. The lower portion of the standard 6 has a similar vertical slideway 12 carrying a vertically movable slide 13 on which is mounted a horizontally 60 slidable carriage 14. The slide 13 carries two series of treeing tools 15 and 16, the tool 15 engaging the quarter of the shoe and the tool 16, known as the rand tool, engaging the 65 sides of the shoe adjacent to the sole.

Between the slides 8 and 13 is positioned a cam bar 20 pivoted at 21 to a bar 19 adjustably fixed to the standard 6 at its lower end and its upper end pivoted at 22 to a similar bar 23 70 likewise adjustable horizontally relative to the standard 6 by which mounting of the cam bar 19 its angular relation to the vertical may be adjusted. The rand tool 16 is provided with a guide roller 24 which rides 75 against the forward cam face 25 of the cam 20 so that the tool is guided to engage the sides of the shoe and closely follow along the sole.

The carriage 14 carries tools 30 which engage the back portion of the shoe, the carriage being positioned closely adjacent to the standard 6 when the slide 13 is raised upwardly so that the tools first engage the back 80 of the shoe adjacent to the sole, the carriage being then moved away from the standard 6 so that these tools are caused to wipe lengthwise along the back seam of the shoe.

The upper and lower slides may be moved in the same manner as described in the Ballard 95 patent hereinbefore mentioned in which the lower slide is first caused to move upwardly to bring the quarter and rand tools into engagement with the shoe and to wipe the sides thereof upwardly and to bring the back tools into 100

engagement with the back seam portion of the shoe. As the lower slide then moves downwardly, the carriage 14 moves horizontally to wipe over the back seam portion of the shoe and the side tools move downwardly, the upper slide following down to bring the tools carried thereby into engagement with the toe portion of the shoe and following the side tools carried by the lower slide as it retracts. 5 Both the upper and lower slides are then moved upwardly, retracting the toe tools and advancing the lower side tools, while the back tools again pass toward the sole of the shoe.

The position of the toe tools, one of the rand 15 tools, and the back tools during one stage of their travel over the shoe is indicated in Figure 2, the quarter tools being omitted for the sake of clearness.

The present invention relates more particularly to the construction and mounting of the various tools. Particularly where the shanks are crooked it is necessary that the tools engaging this portion of the shoe should be permitted considerable motion so as to be 20 able to conform to the change in shoe contour as they pass on to, or away from this portion. In order that the tools may be able to follow this change in contour, they are constructed according to this invention in a manner to 25 permit them a universal rocking movement on their supports, and while in many cases it is not so essential that the quarter tools should be similarly mounted, it is often desirable that they should be so mounted. It is also desirable 30 that the toe engaging tools should also be permitted universal rocking movement in order that they may conform freely and automatically to the contour of the toe of the shoe. Various constructions by which these tools 35 may be given this universal rocking movement 40 are disclosed in Figures 8 to 14 of the drawings.

In Figure 8 a toe tool is illustrated and as shown therein this toe tool is provided with a ball shaped socket 40. This socket may be formed by cutting a slot 41 inwardly from one face of the tool as illustrated in Figure 13, this slot having a rounded inner end, the open end portion of this slot being later filled in by 45 means of a plug 42 having a concaved inner end 43 for engagement with the ball end 44 of a supporting piece provided with a shank 45. Outwardly of the concaved portion 43 the inner end of the plug 42 is inclined as at 46 50 and there is a similar oppositely directed inclination 47 at the base of the slot, these two surfaces defining a flaring opening through which the shank 45 extends. The tool support may be formed in various ways as shown 55 for example in Figures 10, 11 and 12, in each case, however, being provided with a ball shaped end. The shank portion 45 may be formed cylindrical as shown in Figure 11, but preferably it is formed of polygonal cross 60 section either of uniform dimensions through

out its length as shown at 146 in Figure 10 or tapering as shown at 147 in Figure 12. Where the shank portion is formed of polygonal cross section the opening through which it passes in the tool, opposite sides of which are formed by the inclined faces 46 and 47, is also formed of the same polygonal cross section, so that while limited universal rocking of the tool on the support is permitted any substantial swiveling of the tool about the axis of the support is prevented. In this manner the tools are maintained in such relation to the supports that they are always in position to properly engage the shoe as the slides carrying them are moved into operative position. 70 If free swiveling of the tool is permitted, the tools must be formed to properly engage the shoe at any angle or the tools must be held in proper relation to engage the shoe by other means, as for example, by weighting the tools 75 so that they always tend to maintain such a position that they properly initially engage the shoe. Further relative motion between the tools in the shoe would then cause them to automatically assume the proper relations 80 thereto as they pass over the changes in contour of the shoe.

As shown in Figures 10 and 11 each of the tool supports may be provided with an outwardly extending flange portion 50 spaced 85 from the ball end and sleeve portion 51 extending therefrom. This sleeve portion 51 may be fixed in a suitable bracket 55 to which may be fixed the supporting rod 56 by which the tool may be carried on its slide, this being similar to the tool mounting of the Ballard patent hereinbefore mentioned. The hollow sleeve portion 51, however, provides for an additional function in that it may be used to house the inner end of an electrical heating unit 60 as shown in Figure 8. Since these units may be extended closely adjacent to the tools they are more effective in heating these tools than if they were further removed. In some cases also it may be possible to extend 90 the heat unit receiving opening through the sleeve portion 51 and even into the ball head 44. Such a construction is illustrated in Figures 9 and 14 in which it is shown as applied specifically to one of the rand tools 16. This rand tool 16 is shown as having a ball socket formed by cutting in from one face of the tool as shown in Figure 14 and filling the outer portion of this cut by means of a plug 65. Where the shank portion is of sufficiently 95 large cross sectional area, as shown in Figure 9, the socket for the heating element may be readily extended into the ball head being shown therein by dotted lines at 67. In this figure also is disclosed a pair of oppositely disposed ears 68 and 69 on the tool which limit the extent of universal rocking movement and also prevent material swiveling movement about the axis of the support by 100 engaging on the flat faces of the shank portion 105 110 115 120 125 130

47. The tool support for the rand tool is shown as fixed in a bracket 80 having an extension 81 to which the roller 24 may be journaled.

5 With these mountings of the tools as hereinbefore described, it is seen that they are permitted a limited universal rocking movement relative to their supports so that they may automatically conform to the contour 10 of the shoe over which they are being moved, but in the preferred form they are prevented from any material swiveling motion about the axis of the supports so that they are always held so faced that they will 15 properly engage the shoe when first presented thereto.

The tools for engaging the back of the shoe along the back seam being of rigid material are also preferably mounted for limited universal tilting or rocking movement, a preferred construction being shown in Figures 20 3 to 6. Referring first to Figure 3 it will be seen that the carriage 14 has an upwardly extending bracket 90 for pivotally supporting 25 on the pins 91 the levers or arms 92. Each of these levers has fixed at one end a spring 93 by which this end is rocked downwardly under yielding tension toward the carriage 14. Preferably there are two series of such levers 30 arranged one above the other as shown in Figure 3 and means is provided for limiting the extent of tilting movement of these levers as produced by the springs 93. For the upper group of levers this means may consist of set screws 95 extending through the upper ends of the standards 90, the lower ends of these screws being positioned slightly to the opposite side of the pivots 91 from the springs 93 so that the levers are rocked upwardly until they strike these set screws by 35 these springs. The lower pair of levers may have their limits of motion determined by means of studs 96 passing through the support 90 and having eccentric portions 97 with 40 which the upper edges of the levers may contact, the angular adjustment of these eccentric portions determining the amount of movement of these levers. Each of the levers carries at its outer end a support 98 for a tool, 45 each of these supports having socket portions 99 for an electric heating unit 100, each support being seated in a perforation in the lever and fixed therein by suitable means such as a set screw 101.

50 As shown in Figures 3, 4, 5, and 7 the back treeing tools are arranged in pairs, each tool of each pair being carried by its individual lever 92. Each of these tools comprises a block 105 into one side of which is cut a slot 55 106 opening through its rear face and having a spherical shaped inner end portion 107. The upper ball shaped head 108 of the tool support 98 may be passed into the upper portion of each of these slots and when in proper 60 position therein a plug 110 having a concave

inner face 111 mating the ball end may be placed in the outer end of the slot and be fixed therein as by a pin 112. Each of the blocks 105 has a series of fins 120 extending from one edge spaced apart to engage loosely between similar fins of the mating block of the pair and at the fin portion each of the blocks is recessed as at 121 so as to engage over the back seam portion of the shoe and somewhat around on to the side faces thereof.

70 As shown best in Figures 5 and 6 the sides of the socket portion formed by the side walls of the slot 106 are somewhat wider than the shanks 115 of the support 98 so that a limited rocking movement of the blocks 105 on their supports from and toward the mating block of the pair is permitted while the end faces of the slots and of the plugs as 116 and 117 flare very considerably thus permitting a more extensive endwise rocking movement of the blocks. As shown in Figure 7 the shanks of 75 the supports 98 may be of polygonal cross section.

80 When the lower slide 13 is raised upwardly the quarter and rand tools first engage the shoe and during their continued upward movement the blocks 105 press against the back portion of the shoe, the springs 93 yielding as the carriage 14 continues its upward movement with the slide 13 and at a suitable 85 time the slide 14 is then given its outward movement to cause the blocks 105 to be drawn away from the sole portion of the shoe so as to wipe over the back seam portion thereof. The mounting of the blocks relative to each other 90 and relative to their supports permits them to conform automatically to the changes in contour of the portion of the shoe engaged thereby during this motion.

95 It will thus be seen that the various tools are so mounted as to permit them to conform closely to the considerable irregularities of contour of the shoe being operated upon and due also to the efficient manner of heating the tools they are enabled to tree the shoes in a 100 highly efficient and expeditious manner.

105 Having thus described certain embodiments of this invention it should be evident to those skilled in the art that various changes and modifications might be made therein 110 without departing from its spirit or scope as defined by the appended claims.

I claim:

1. In a treeing machine, treeing tools, and an element supporting each of said tools with a capability of limited universal rocking movement, said elements and tools being formed complementally in a manner to prevent substantial swiveling of the tools relative to their supporting elements.

120 2. In combination, a treeing tool having a ball socket therein, and a support for said tool having a ball end fitting in said socket and a shank portion extending therefrom, said shank portion and cooperating socket

125

130

portion being formed complementally to prevent substantial swiveling of said tool relative to said support but permitting limited universal rocking movement thereof.

3. In combination, a treeing tool having a ball socket therein, and a support for said tool having a ball end fitting in said socket and a shank portion extending therefrom, said shank being formed polygonal in cross section and the socket portion within which said shank rides being of similar polygonal cross section and flaring toward its outer end to permit universal rocking movement of said tool relative to said support but preventing substantial relative swiveling movement.

4. In a treeing machine, a treeing tool, a support for said tool permitting universal rocking movement of said tool relative thereto but limiting said movement, and a heating element carried by said support adjacent to said tool.

5. In a treeing machine, a treeing tool, a support for said tool permitting universal movement of said tool relative thereto but limiting said movement, said support being recessed adjacent to said tool, and a heating element in said recess.

6. In a treeing machine, a treeing tool having a ball socket, a support for said tool having a ball head for engagement in said socket and a recess extending into said ball head, and a heating element in said recess.

7. In a treeing machine, means for supporting a shoe to be treed, a carriage movable relatively toward and from a shoe on said supporting means, and a treeing tool universally rockable relative to said carriage and carried thereby in position to act on the shoe as the carriage is moved.

8. In a treeing machine, a pair of tools engageable with the rear portion of a shoe and movable along the back seam thereof, said tools comprising a pair of blocks having interengaging adjacent portions, and recessed at said portions to engage about the back portion of a shoe, and means for supporting said blocks permitting them independent limited universal rocking movement whereby they may conform to different contours of the shoe.

9. In a treeing machine, a pair of tools engageable with the back of a shoe and movable therewith, said tools comprising a pair of blocks each having fins engageable between fins of the adjacent block, said blocks being cut away at said fins to engage over the back of a shoe, each of said blocks having a spherical socket opening through its rear face, and a supporting member having a spherical head seated in each socket.

10. In a treeing machine, means for supporting a shoe to be treed, a carriage movable relative to said support from and toward the back of a shoe carried by said support and also movable lengthwise of such back, a treeing tool rockably supported on

said carriage, a spring for pressing said tool toward the shoe, and a stop for limiting the movement of said tool due to said spring.

11. In a treeing machine, means for supporting a shoe to be treed, a carriage movable relative to said support from and toward the back of a shoe carried by said support and also movable lengthwise of such back, a lever fulcrumed on said carriage, a treeing tool carried on one end of said lever, and a spring engaging said lever for pressing said tool yieldingly toward the shoe.

12. In a treeing machine, means for supporting a shoe, a carriage movable toward and from the back portion of a shoe on said support and longitudinally of said back portion, a pair of levers pivoted to said carriage, a ball joint element carried by each of said levers, a treeing tool carried by each lever and having a mating ball joint element whereby said tools are mounted for universal rocking movement, said tools being positioned adjacent to each other and each having fin portions lapping past the fin portions of the other, said tools having a recess cut therein at said fin portions within which the back portion of the shoe engages, and springs engaging said levers and pressing said tools toward a shoe on said support.

13. In a treeing machine, means for supporting a shoe, a carriage movable toward and from the back portion of a shoe on said support and longitudinally of said back portion, a pair of levers pivoted to said carriage, a ball joint element carried by each of said levers, a treeing tool carried by each lever and having a mating ball joint element whereby said tools are mounted for universal rocking movement, said tools being positioned adjacent to each other and each having fin portions lapping past the fin portions of the other, said tools having a recess cut therein at said fin portions within which the back portion of the shoe engages, and springs engaging said levers and pressing said tools toward a shoe on said support, and means for adjustably limiting the extent of such pressing action.

14. In a treeing machine, means for supporting a shoe, a carriage movable relative to a shoe on said support, an arm carried by said carriage, a tool support carried by said arm, a tool universally rockable relative to and carried by said support, means acting on said arm for pressing said tool towards the shoe, and tool heating means carried by said support.

In testimony whereof I have affixed my signature.

WILLIAM A. COPELAND.
